[57] CLAIM

The ornamental design for a dental articulator, as shown and described.

DESCRIPTION

FIG. 1 is a perspective view of the dental articulator showing our new design;

FIG. 2 is a perspective view thereof in the folded position;

FIG. 3 is a perspective view thereof with a model of a patient's teeth being supported upon a platform during measuring;

FIG. 4 is another perspective view thereof similar to FIG. 3;

FIG. 5 is a left-side elevational view thereof;

FIG. 6 is a right side elevational view thereof;

FIG. 7 is a front elevational view thereof;

FIG. 8 is a rear elevational view thereof;

FIG. 9 is a top plan view thereof; and,

FIG. 10 is a bottom plan view thereof.

FIG. 1

FIG. 6

FIG. 5

FIG. 7

FIG. 8

FIG. 9

FIG. 10
